UNITED STATES PATENT OFFICE

2,424,944

FOLDING STOCK FOR AUTOMATIC FIREARMS

George William Patchett, Chigwell, England

Application February 23, 1944, Serial No. 523,569
In Great Britain May 26, 1943

15 Claims. (Cl. 42—72)

1

This invention relates to improvements in folding stock for automatic firearms, and has more particular reference though without limitation to the class of weapons known as machine carbines, and the object of the invention is to provide carbines of the above type with a hinged and foldable butt capable of extension rear of the carbine for operative use, but collapsible at will and foldable about the under side of the weapon with no loose part or parts extending beyond the confines of the weapon itself. A further object of the invention is to so devise the said butt that the operation of opening to operative position and folding to an inoperative condition can be achieved with the minimum of effort and time, and of providing a butt that when extended is rigid in all directions.

To secure the butt in a state of fixity for operation, a locking device is provided forming part of or attached to the end cap or recoil spring retainer, the latter being capable of small movement axially of the spring casing, the main recoil spring automatically locking said cap to the butt, and means whereby said cap after engagement is prevented from subsequent movement except at will.

By reason of the construction employed, the additional weight is small and there are no projections when the butt is folded likely to catch in loose equipment of the user. With the butt folded the balance of the carbine is not impaired and the weapon can be used folded for firing at close range, or with the butt extended the weapon can be fired from the shoulder, as a carbine, at longer ranges. With the butt in the folded position accessibility to the trigger mechanism is not impaired and the balance of the weapon remains satisfactory.

The invention consists of an articulated triangular butt for machine carbines and the like comprising a forked compound upper main member pivoted to the weapon at the rear of the pistol stock and adapted in its operative position to engage with and be locked to the carbine end cap, a strut hinged to said main member intermediate its length, a butt plate hinged to said strut and urged under spring pressure to engage at its end remote from its pivot the terminal of the upper main member and be locked thereto. The carbine end cap with its butt locking device is fixed to the spring casing with a bayonet joint. The end cap has sufficient axial movement, against the recoil spring pressure, to enable the lugs on the forked main member to be raised to the required position and locked therewith by the re-

2

turn movement of the end cap under the recoil spring pressure. An independently operated locking means prevents axial movement of the end cap unless desired. The butt strut is provided with a spring-loaded plunger engaging the tail of the butt plate, said plunger carrying a hook pin capable of snap locking the butt in its folded condition to the forward end of the barrel casing of the carbine.

10 In order to more fully describe the invention, reference is made to the accompanying drawings, wherein a preferred embodiment of the said invention is set forth and wherein:

Fig. 1 is a part sectional elevation of a machine carbine fitted with the folding butt in its extended or operative position,

Fig. 2 is an elevation of the carbine with the butt in its folded position,

Fig. 3 is a plan of Fig. 1,

20 Fig. 4 is a cross section at line A—A, Fig. 1,
Fig. 5 is a cross section on line B—B, Fig. 1,
Fig. 6 is an end elevation of the back cap.

Fig. 7 is a cross section of the compound main upper member on line C—C, Fig. 1,
25 Fig. 8 is a cross section of cap on line D—D,
Fig. 1.

Fig. 9 is a detail view of an alternative method of locking the butt to the barrel casing cap.

Referring to the drawings, the carbine illustrated has a barrel casing 1, a pistol grip 2, a trigger 3, a trigger guard 4, a recoil spring casing 1a, and an end cap 6. Attached to the recoil spring casing 1a is a bracket 7 (see Fig. 5) having opposed circular bushes 8 upon which are pivotally mounted the extremities of the forked forward end 9 of the compound upper main member referred to as a whole as F. These arms are secured in position on the bushes 8 by pins 10 which are secured in position by cross pins 11. The forked arms of the member F are contracted at 12 and provided with a yoke plate 13 at the point of contraction, the member F extending rearward and terminating with a second yoke plate 14. Pivoted to the member F at 15 is a strut G preferably formed as a tubular entity and having a spring stop 16, a spring 17 and a sliding plunger 18 carrying a catch 19. The plunger 18 is recessed as shown at 20 and accommodates in said recess a hinge pin 21 upon which butt plate H is pivoted. The butt plate is provided with a contact nose 22 engaging the end of the sliding plunger 18 whereby the said butt plate is normally pressed to occupy a spring-controlled position whereby its upper end 23 can engage the terminal of the member F. A step 25 integral

with the butt plate H accommodates the under side of the member F and the butt plate is provided with ears 26 which elastically engage and lock to the member F. The strut G is shaped as at 30 adjacent its pivot 15 to occupy a definite angular position by bearing against yoke plate 13. The said yoke plate can terminate with two ears 31 which are adapted to be locked into recesses 32 formed in a lug 33 attached to the bayonet jointed end cap that is secured to the terminal portion of the recoil spring casing 1 (see Figs. 4 and 6). The forked member F pivoted at 10 is made of sufficient width to swing clear of the pistol grip stock 2 and nest on the under side of the carbine in the position shown in Fig. 2. When the folding butt is swung into its forward inoperative position the strut G nests between the side pieces of the member F. The butt plate H is first drawn forward, whereby the contact nose 22 presses back the sliding bolt 18, allowing the catch 19 to enter a slot 35 in the substance of the carbine gun barrel casing 1.

By now folding the butt plate rearward and inward, the catch 19 locks the butt assembly into the position shown in full line in Fig. 2, the butt plate being folded backwards so that its ears 26 grip the outer sides of the compound member F. The catch 19 locks the butt assembly into position shown in Fig. 2.

The end cap 6 is locked against axial movement by means of a lock-bar 40 pivoted at 41 between lugs 42; said bar 40 may be chamfered at its rear portion 43, and is provided with a spring 44 and an inserted limiting stop 45. The rearward end of the lock-bar 40 bears against the forward face of the cap 6.

The operation of the device is as follows:

Assuming the butt to be in its folded and nested condition as shown in Fig. 2, the butt plate H is pulled in an arcuate direction about its pivot 10 which causes the contact nose 22 to press back the sliding bolt 18 and catch 19, disengaging thereby the members G and F from the gun barrel casing. The butt is now free to swing about its pivot 10, into the position shown in Fig. 1. The locking bar 40 is now tilted about its pivot by applying pressure over the insert 45 which tilts the bar out of the path of movement of the cap 6, which is free to be pressed forward against the recoil spring 34. This enables the ears 31 of the yoke plate 13 to enter the slots 32 in the lug 33 on the cap, and by leaving go of the cap the recoil spring 34 forces the cap back again to its limiting position as shown in Fig. 1, and the locking bar 40 returns to its normal locked position, preventing any movement of the cap. By these means the member F is now securely locked in its rearward and extended position. The butt plate H is now grasped and the strut G caused at its upper end 30 to contact with the yoke plate 13. The underside of the member F engages in the step 25 on butt plate H which is then held against the member F by the spring-loaded plunger 18 and forms in conjunction with the strut G a stiff triangular arrangement. The width of the butt plate may be varied within reasonable limits depending upon calibre of the carbine with which it is employed; but the dimensions shown in the plan of Fig. 3 provide a sufficient surface for the user not to feel the effect of constant firing. The folding butt in its operative position constitutes a rigid entity with the carbine itself. When the butt is collapsed for the purposes of folding in its nested position beneath the barrel of the carbine, ample space for trigger operation

is available. Further, the butt formed as a skeletonised entity possesses but little weight, does not upset the balance of the weapon in use, and is, moreover, capable of being folded within the confines of the gun so that no protruding part occurs when the butt is folded into its inoperative position.

Instead of employing the ears 31 on the plate 13 to cooperate with the recesses 32 on the cap 6 to secure the butt in its operative position, a pair of separate lugs 31a may be fitted to the forked arms of the member F and arranged to engage in notches in the rear side of the lug attached to the cap, as shown in Fig. 9, the operation being otherwise the same as hereinbefore described in connection with the lugs 31.

I claim:

1. The combination of an automatic firearm comprising a casing having a main recoil spring therein, a butt pivoted to said casing to swing into an extended position at the rear of the firearm and into a folded position along the length thereof, and means biased by said main recoil spring for holding the butt in said extended position.

2. The combination of an automatic firearm comprising a casing having a main recoil spring therein, a butt pivoted to said casing to swing into an extended position at the rear of the firearm and into a folded position along the length thereof, and means biased by said main recoil spring for locking the butt in said extended position and releasable by movement of said means against the action of said spring.

3. The combination of a firearm comprising a casing having a recoil spring therein, a cap engaged and movable by said spring axially of said casing and providing a closure for the rear end of said casing, a butt pivoted to said casing to swing into an operative position to extend rearwardly from the firearm and into a folded position along the length thereof, and means on said cap and butt cooperative to hold the butt in said rearwardly extended operative position under the action of said spring and releasable by movement of said cap axially of said casing against the action of said spring.

4. A folding butt for a firearm consisting of three members a pair of which are pivotally connected and the third member pivotally connected to one of said pair of members and engageable with the other of said pair of members to form a triangle, one of said members having an extension provided with means for pivotally attaching it to a firearm, and cooperating means on the firearm and the butt for locking the latter in extended position at the rear of the firearm.

5. The combination according to claim 3, wherein said holding means comprise lugs on said butt constructed and arranged to engage and interlock with recesses formed in a lug integral with said cap.

6. The combination according to claim 3, wherein said cap has a bayonet joint connection with said casing, and has limited axial movement on said casing to lock and release the butt.

7. A butt for a firearm comprising a main member having means at one end for pivotally attaching it to a firearm, a strut member pivoted at one end to said main member at a point between its ends, and a butt plate member pivotally connected to the other end of said strut member and engageable with the end of said main member opposite to its pivoted end to form a rigid

triangular structure, and locking means between the strut member and the butt plate member.

8. A butt for a firearm, comprising a main member having means at one end for pivotally connecting it to the underside of a firearm to swing into an extended position at the rear of the firearm and into a folded position beneath the firearm, a strut member pivoted at one end to said main member at a point between its ends, and a butt plate member pivoted to the other end of said strut member and engageable with the end of the main member opposite to its pivoted end to form with said main and strut members a rigid triangular structure.

9. The combination according to claim 3, including a hand stock and a trigger on the underside of said firearm, and wherein said butt is forked to provide a pair of limbs of a length to pass the hand stock and trigger while being swung into a folded position along and beneath the firearm.

10. The combination according to claim 3, wherein said casing on said firearm is provided with a slot in its underside, and a spring-impelled catch on said butt engageable in said slot to lock said butt in fixed folded position beneath the firearm.

11. The combination of a firearm comprising a casing having a slot in its underside, a butt comprising a main member having means at one end thereof for pivotally connecting it to the firearm to swing into an operative position extended from the rear of the firearm and into a folded inoperative position beneath the firearm, a strut member pivoted at one end to said main member at a point between its ends, a butt plate member having a pivot pin at one end pivotally connecting it to the other end of said strut member, means at the opposite end of said butt plate member to cooperate with the end of said main member remote from its pivoted end to form a rigid triangular structure, a spring-loaded plunger in the end of said strut member adjacent to said pivot pin and acting on the adjacent end of said butt plate member to hold it in cooperating relation with said main member, and a catch carried by said plunger and engageable in said slot in said casing to releasably hold the butt in folded position beneath the firearm.

12. The combination according to claim 11, wherein said spring-loaded plunger is normally active to hold said butt plate member in folded relation with said main member and is retracted

to release said catch by pivotal movement of said butt plate member into an angular position relatively to said main member.

13. A folding butt for firearms, comprising a main member having means for pivotally connecting it to a firearm, a strut member pivotally connected at one end to said main member, means for limiting the angular movement of said strut member about its pivotal connection relatively to said main member, a butt plate having a pivot pin connecting it to said strut member, a spring-impelled sliding plunger at the end of said strut member remote from its pivotal connection to said main member and recessed to accommodate said pivot pin, said butt plate having a nose contacting said plunger whereby said butt plate has impelled angular movement about said pivot pin for operative assembly of the butt.

14. A folding butt for firearms, comprising a main member having pivot means for connecting it to a firearm, a strut member hinged at one end to said main member, and a butt plate having a pivot pin connecting it to said strut member, said butt plate being of channel cross-section and having terminal ears thereon, said ears remote from said pivot pin being engageable with said main member at the end thereof remote from said pivot means, locking means on said butt plate to cooperate with said end of said main member to form with said main and strut members a rigid structure, and said ears adjacent to said pivot pin carrying said pin, said butt plate having a contact nose thereon adjacent to said pivot pin, and a sliding plunger on said strut and engaging said nose.

15. A folding butt according to claim 14, wherein said plunger is spring-loaded, and acts to lock said butt plate to said end of said main member for operative use of the butt, and to hold the butt plate in inoperative relation to said main member when folded.
